UNITED STATES PATENT OFFICE.

PAUL R. FINCH, OF DES MOINES, IOWA, ASSIGNOR OF ONE-HALF TO ALVAH C. WHITE,
OF DES MOINES, IOWA.

PUMP.

Application filed December 27, 1923. Serial No. 682,873.

The object of this invention is to provide an improved construction for a rotary pump.

A further object of this invention is to provide an improved means for separating 5 a pump chamber into two compartments, including a hinged plate having sliding connections with an impeller and engaging a wall of the chamber.

A further object of this invention is to 10 provide efficient means, so arranged as to prevent leakage, for bridging the space between a movable impeller and a wall of a chamber, for dividing said chamber into two separate compartments.

15 My invention consists in the construction, arrangement and combination of elements hereinafter set forth, pointed out in my claims and illustrated by the accompanying drawing, in which—

20 Figure 1 is an end view, with one end plate removed, showing one form of rotary pump embodying my improvements.

Figures 2 and 3 are similar views showing 25 different forms of rotary pumps embodying my improvements.

Figure 4 is a side elevation of the pump shown in Figure 1.

Figure 5 is a detail view, partly in section, 30 at right angles to Figure 1, showing the hinged plate and a portion of the impeller blade to which it is slidingly connected.

Figure 6 is a detail view of the members shown in Figure 5, detached.

In the construction of the device as shown 35 in Figures 1, 4, 5 and 6 the numeral 10 designates generally a casing formed with a substantially cylindrical chamber 11 and a chamber 12 communicating therewith by means of a passage 13 extending from end to end of said chambers. As shown, the chamber 12 is at the base of the casing and the chamber 11 is superposed relative thereto, but the position may be reversed or the pump placed in any suitable position for operation. The ends of the chambers of the casing are closed by means of end plates 14, 15 held in place by means of bolts extending through holes therein and through registering holes 16 in the wall of the casing. A shaft 17 is mounted longitudinally and axially of the cylindrical chamber 11, is journaled for rotation in bearings 18 in the ends plates 14, 15, projects therefrom and is provided with one or more belt or fly wheels 19, 20, in this instance two in

number, one at each end of the shaft. A cylindrical impeller 21, of less diameter than the cylindrical chamber 11, is mounted in said chamber and is formed with a central, longitudinal bore 22 through which said shaft extends loosely. Formed on or fixed to the shaft 17 are one or more eccentrics 23 fitting the bore of the impeller 21, and said eccentrics serve to hold the impeller eccentrically of the chamber 11 and to give it a 60 circular orbital movement therein, in contact with the chamber walls, when the shaft is rotated. The eccentrics may be of any desired number and fill any desired portion of the length of the bore of the impeller, 65 one only of said members being shown, in Figure 1. Formed on or fixed to the impeller 21 at one point of its periphery, and extending radially therefrom, is a blade 24 which projects through the passage 13 and 70 into the chamber 11. A plate 25 extends longitudinally of the outer portion of the chamber 12, and in this instance is arranged centrally thereof and opposite the passage 13 and blade or wing 24. The plate 25 has 75 one margin in oscillating contact with the inner surface of the wall of the chamber 12 and in this instance such margin of the plate is formed on an arc and extends with- 80 in an arcuate groove or concavity in said wall, the better to prevent fluid leakage between said members. The plate 25 is formed with trunnions 26 on its ends, which trunnions are journaled in bearings 29 formed in the end walls 14 and 15 of the housing. 85 Plates 27, 28 are mounted on opposite sides of and secured rigidly to the lower portion of the impeller blade 24 by means of bolts 29. The plates 27, 28 project beyond the margin of the blade 24 and slidingly engage 90 the partition plate 25. Preferably a number of shims such as 30 are originally mounted between the blade 24 and plates 27, 28, which may be removed from time to time as wear occurs to maintain a tight fit between the plates 27, 28 and partition plate 25 and 95 prevent fluid leakage therebetween. The blade 24, partition plate 25 and clamping plates 27, 28 together form a partition dividing the chamber 12 longitudinally into 100 two compartments, and said members extend from end to end of said chamber and have a working contact with the end walls of the housing, such that comparatively little leakage of fluid may occur between 105 110

them. The walls of the casing are formed with ports 31, 32 opening to the chamber 12 on opposite sides of the partition therein, and said ports are provided with suitable connections (not shown) and so arranged as to be used as inlet and exhaust ports, one answering for the inlet and the other for the exhaust of fluid from the pump.

In practical use the pump may be driven by any desired means, and be employed either as a compressor or an exhaust pump. As the shaft 17 is rotated the cams 23 thereon cause the cylindrical impeller to revolve in its orbit, having a moving contact at changing points of its periphery with the periphery of the cylindrical chamber 11, and such travel may be in either direction. As the impeller moves in the manner described the blade 24 is caused to oscillate vertically and laterally, and the passage 13 is of sufficient width to permit such travel without contact of the blade with its margins. The movement of the blade causes a corresponding movement of the clamping plates 27, 28, which slide on the partition plate 25, causing it to rock on its trunnions, at all times maintaining a contact at its lower margin with the bottom of the chamber 12. Thus the two compartments of the chamber are kept separate, and fluid in one of said compartments is drawn by the movement of the rotary impeller into the cylindrical chamber and carried in an annular path therein, ahead of the point of contact of the impeller, into the opposite compartment of the chamber 12 and out of the exhaust port.

The impeller 21 may be formed with a number of longitudinal openings 33 extending therethrough, within which may be placed wicks or masses of absorbent material used as a vehicle for lubricating material and adapted to lubricate and prevent friction particularly between the ends of the impeller and the casing walls.

My invention resides particularly in the peculiar form and arrangement of the rocking partition between the rotary impeller and the opposite wall of the casing through the medium of the partition plate 25, and such construction may be employed in many forms of rotary pump.

In Figure 2, I have shown my improvement applied to a form of pump adapted to be constructed of sheet metal, a sheet 34 is bent and curved to the desired shape to produce the chambers of the pump casing. The sheet or wall 34 is formed with flanges 34' apertured at 16 to receive bolts by which it is bolted to the end plates of the casing. The sheet 34 is so formed as to produce a substantially cylindrical chamber 11" and an ovate chamber 12" communicating therewith through a passage 13", formed by terminating one margin of the sheet opposite

a wall common to said chambers. The shaft 17" with its eccentrics 23" is similar to what has been described, and the impeller is formed of two concentric sheets 21" suitably connected, the inner sheet receiving contact of the cams 23" and the outer having oscillating contact with the periphery of the cylindrical chamber 11". One portion of the outer sheet 21" is extended beyond the periphery thereof in substantially tangential relation to form an impeller blade 24" projecting through the passage 13" into the chamber 12". A rocking partition plate 25", exactly like those previously described, is formed with trunnions 26" journaled in the end walls of the casing, said partition plate having oscillating contact at one long margin with the wall of the chamber 12". The impeller blade 24" extends past the opposite margin of the plate 25", and in sliding contact therewith, and a clamping plate 27" is mounted parallel thereto, and in sliding contact with the other face of said plate 25". The clamping plate 27" is spaced from the impeller blade 24" by a spacing bar 28" and secured thereto by bolts 29". Ports 31", 32" open to the chamber 12" on opposite sides of the movable partition thus formed, and in this instance said ports are formed in one end wall or plate 14" of the housing.

In Figure 3 is shown a form of pump equipped with my improvement, in which a substantially cylindrical casing 35 is formed with a single cylindrical chamber 36 in which a shaft 37 is arranged axially and is provided with cams 38. A cylindrical impeller 39 is mounted in the chamber and is formed with a cylindrical bore 40 receiving the shaft and engaged by the cams, and by said cams the impeller is held in eccentric position within the chamber and caused to travel in a circular orbit in contact with the wall of the chamber. A partition plate 41 extends longitudinally of the chamber and is formed with trunnions 42 journaled in the ends thereof, and one margin of said plate extends within a concaved channel 43 extending longitudinally of the wall of the chamber. At one point in its periphery the impeller 39 is formed with a longitudinal dovetailed groove 44 within which is snugly mounted an impeller blade or wing 45, projecting at one margin from said groove and formed with a longitudinal channel or slide seat 46 having sliding engagement with one marginal portion of the partition plate 41. Near the movable partition thus formed, and on opposite sides thereof, are ports 47, 48 formed preferably in one end wall of the casing 35. This is a compact form of pump, as the chamber need not be of much greater diameter than the impeller, the blade 45 may be seated a considerable distance in said impeller, and the inner

margin of the partition plate 41 may even project somewhat within the periphery of the impeller as shown.

In actual practice it may be desirable to leave a very slight clearance between the periphery of the impeller and the wall of the chamber to prevent noise in use, but said members are in substantial contact.

I claim as my invention—

10. 1. A pump comprising a cylindrical chamber, a second chamber communicating with the first and having intake and exhaust ports, an eccentrically movable cylindrical impeller within the said cylindrical chamber having contact at one point of its periphery with the wall of the latter, a blade projecting from the periphery of the impeller and extended into the second chamber, a partition plate mounted for oscillation in the second chamber and having one margin extended into oscillating contact with a wall thereof, and sliding connections between said impeller blade and partition plate, said impeller blade, partition plate and sliding connections constituting a movable partition across said second chamber between the intake and exhaust ports. 65
20. 2. A pump comprising a cylindrical chamber, a second chamber communicating with the first and having intake and exhaust ports, an eccentrically movable cylindrical impeller within the cylindrical chamber having traveling contact at one point of its periphery with the wall of the latter, a blade projecting from the periphery of the impeller and extended into the second chamber, a partition plate having trunnions at its ends journaled in the walls of the second chamber and having one margin in movable contact with a wall of said chamber opposite the cylindrical chamber, and a plate fixed to said blade and having sliding contact with said partition plate, whereby a movable and extensible partition is provided across said second chamber between the intake and exhaust ports. 60
30. 3. A pump comprising a substantially cylindrical chamber, a second chamber communicating with the first and having intake and exhaust ports, an eccentrically movable, substantially cylindrical impeller within the cylindrical chamber having traveling contact with the wall of the latter, a blade projecting from the impeller and extended into the second chamber, a partition plate mounted for rocking movement in the second chamber and having one margin 70 rounded and in contact with a wall of said chamber between the intake and exhaust ports, and a plate fixed to said blade and having sliding contact with and throughout the length of said partition plate. 75
40. 4. In a rotary pump having a casing and an impeller mounted for orbital travel therein, said casing being formed with intake and exhaust ports, the combination with said casing and impeller of a partition plate mounted for rocking movement in said casing and having one margin in contact with a wall thereof between the intake and exhaust ports, and sliding connections between said impeller and partition plate 80 whereby a movable partition is formed between said intake and exhaust ports. 85
45. 5. In a rotary pump having a casing and an impeller mounted for orbital travel therein, said casing being formed with intake and exhaust ports, the combination with said casing and impeller of a partition plate mounted for rocking movement in said casing and having one margin in contact with a wall thereof between the intake and exhaust ports, and sliding connections between said impeller and partition plate 90 whereby a movable partition is formed between said intake and exhaust ports. 95

and exhaust ports, an eccentrically movable cylindrical impeller within the cylindrical chamber having traveling contact with the wall of the latter, a blade projecting from the periphery of the impeller and extended into the second chamber, a partition plate having trunnions at its ends journaled in the walls of the second chamber and having one margin in movable contact with a wall of said chamber opposite the cylindrical chamber, and a plate fixed to said impeller blade and having sliding contact with said partition plate, whereby a movable and extensible partition is provided across said second chamber between the intake and exhaust ports.

4. A pump comprising a substantially cylindrical chamber, a second chamber communicating with the first and having intake and exhaust ports, an eccentrically movable, substantially cylindrical impeller within the cylindrical chamber having traveling contact with the wall of the latter, a blade projecting from the impeller and extended into the second chamber, a partition plate mounted for rocking movement in the second chamber and having one margin 70 rounded and in contact with a wall of said chamber between the intake and exhaust ports, and a plate fixed to said blade and having sliding contact with and throughout the length of said partition plate. 75

5. In a rotary pump having a casing and an impeller mounted for orbital travel therein, said casing being formed with intake and exhaust ports, the combination with said casing and impeller of a partition plate mounted for rocking movement in said casing and having one margin in contact with a wall thereof between the intake and exhaust ports, and sliding connections between said impeller and partition plate 80 whereby a movable partition is formed between said intake and exhaust ports. 85

Signed at Des Moines, in the county of Polk and State of Iowa, this 19th day of December, 1923.

PAUL R. FINCH.
